UNITED STATES PATENT OFFICE.

JAMES VRBA, OF MARSHALLTOWN, IOWA.

LOCK.

Application filed May 21, 1926. Serial No. 110,613.

The invention relates generally to improvements in locks and has particular reference to keyless permutation or combination locks, or the like, and has among its objects to provide a new and useful device of this character which will provide a high degree of security against unauthorized manipulation.

It is a further object of this invention to provide a plurality of independently operable rotatable members having a co-operation with a single slidable plate member to retain the integral lock bolt in locked or unlocked position. The unlock position of the lock bolt being permitted only in one pre-arranged position of the rotatable members.

Another object of the invention is to provide such rotatable members with means for varying the setting thereof for varying the combination of letters or numerals of the controlling exterior dials to afford the unlocking of the lock bolt at different combinations of such letters or numerals.

With these and other objects in view, my invention consists in the novel combination, construction and arrangement of the parts and members shown in the accompanying drawings, described in the following specifications and particularly pointed out in the appended claims.

In the drawings: Figure 1, is an elevation of a lock embodying my invention, showing particularly the exterior view of the controlling dial on the face of a door equipped with same;

Figure 2, is a cross section taken on line 2-2 of Figure 3;

Figure 3 is a plan view of the lock with the cover plate removed showing the mechanism thereof in position to permit the unlocking of the lock bolt;

Figure 4, shows a view similar to Figure 3, with one of the rotatable members positioned to retain the lock bolt in unlocked position.

Referring to the drawings which show a preferred embodiment of the invention, 10 indicates the casing having a side 11 riveted thereto and provided with openings 12 for screws 13 which securely retain the casing in a door portion indicated by 14. The bottom or side 10^A of the casing 10 is cast with an integral lug 15 which acts as a sup-

port of the screw 16 which retains the removable cover plate 17. 55

The lock bolt 18 has sliding movement through an opening in the side member 11 and is formed integrally with a slidably mounted plate portion 18^A. 60

An auxiliary keeper bolt 19 is provided which also operates slidably through an opening in the side member 11 and which is also provided with an integrally formed slidably mounted plate portion 19^A. The keeper bolt is formed with the usual beveled face 19^B to afford its inwardly slidably action upon the closing of the door. A single leaf spring 20 having an intermediate loop connection about the lug 10^B is arranged to normally retain the lock bolt and keeper bolt in outward position by the engagement of its ends with the inner ends of the plate portions 18^A and 19^A. 65

The keeper bolt 19 is provided with an integral projection 19^C which is adapted to engage the front end of the plate 18^A to thereby simultaneously open or shift the lock bolt 18 upon the rotation of the handle 21 during the unlocking movement of the keeper bolt 19. When, however, the lock bolt 18 is in the position shown in Fig. 3 with the combination locking mechanism set to afford its inward movement, the handle 21 may be rotated (anti-clockwise) which 70 will cause the lug 22 to engage the keeper bolt 19 within the recess 19^D to move same toward the right or inwardly and simultaneously through the engagement of the projection 19^C with the plate 18^A move the lock 75 bolt inwardly to unlocked position. 80

In order to maintain the lock bolt 18 in unlocked position, I provide the slot 30 of the upper right hand wheel 29 with an arcuate slot extension 30^A which permits a slight additional rotation of same to the position shown in Figure 4, whereby the lug 35 is so locked within the extension slot 30^A that an outward movement of the lock bolt plate 18^A by the spring 20 is prevented. 85

The lock here shown is provided with three controls equipped with knobs 23 set screwed to the shafts 24 which are of square cross section. A pair of dials 25 is provided for and fixed to each shaft 24. The dials 25 are provided with numerals 25^A (or letters) arranged to register with the indicators 26. 100

Each shaft 24 extends through a square opening of an indicator member 27, the hub extensions of which are rotatably mounted in openings provided in the side 10^A and cover plate 17. The indicator member 27 of each control being fixed for relative movement with the dials 25. Each indicator member 27 is also provided with an integral arm 27^A within the end of which is fixed a pin 28.

10 The lock bolt plate 18^A is slotted as at 18^C to permit the passage of the hub extensions of the members 27 through same.

Upon the hub of each of the members 27 is a freely mounted wheel 29 having a slot 30 and a corrugated periphery. A plain disk wheel 31 of a slightly larger diameter is riveted to one side of each of the corrugated wheels 29, and each disk wheel 31 is also provided with a radial slot in register with the slot 30.

15 The three disk wheels 29 as shown in Fig. 3, are so positioned that the integral lugs 35 of the lock bolt plate 18^A readily pass into the slots 30 during the inward unlocking movement of the plates 18 and 19. It is obvious, that the inward unlocking movement of the lock bolt 18 is not permissible unless all three disk wheels 29 are positioned as shown in Figure 3, to permit the passage 20 of the lugs 35 within the slots 30.

25 The disk wheels 31 might be omitted, but I prefer to employ same as they act as a guide for the spring 32 which is of irregular shape and which spring 32 is securely held in the slot 15^A in a manner to continually engage the corrugated peripheries of the three wheels 29 to thus retain them in predetermined positions. The corrugated edge of the wheels 29 also has the function of preventing the detection of the position of the slot 30 as the spaces between the outstanding corrugations are equal to the width of the slot 30.

30 Each of the wheels 29 is provided with a plurality of openings 33 arranged in a circle therein and consecutively numbered or lettered on the face thereof as shown in Figures 3 and 4. These openings 33 are adapted to receive the pins 28 of the arms 27^A of the indicators 27 whereby the indicators 27 will move relatively with the wheels 29. As stated above, the dials 25 are fixed for relative movement with the indicators 27, that is, the indicator arm 27^A is always positioned relatively to the dial 25 under the numeral 1 thereon, but the relative position of the indicator arms 27^A and the wheels 29 may be varied as for instance, by reference to Figures 3 and 4, the upper left hand wheel 29 is shown with its co-operating indicator arm 27^A positioned within the opening numbered "11", thus causing a registration of the exterior control dial 25 with its number "6" in register with the fixed indicator 26, but if the respective indicator arm 27^A be moved to

a setting of the pin in the opening numbered "7", then the exterior control dial 25 will show its number "10" in register with the indicator 26. Thus all three indicator arms 27^A may be variably set to thereby vary the 70 settings of exterior dials 25.

I claim:

1. In a lock of the kind described, and in combination, a slidably mounted lock bolt, a 75 slidable keeper bolt, a plurality of independently mounted rotatable members each having a single radial slot therein, each of said rotatable members having the periphery thereof corrugated and the width of the spaces between said corrugation being equal 80 to the width of said slot, resilient means engaging said corrugated peripheries of said members, a single spring exerting pressure on said lock bolt and said keeper bolt tending to retain same in locked position, a plurality of lugs connected with said lock bolt, a plurality of separate and independently mounted controls for said rotatable members, and a dial for each of said controls adapted for setting at varying indications, said rotatable members being adjustable to varying relative positions to said controls whereby said slots in said rotatable members may be prearranged to align with said lugs at varying indications of said dials to permit the 95 inward movement of said lock and keeper bolts.

2. A lock as embodied in claim 1, and including an arcuate slot extension in one of said slots of one of said rotatable members whereby the rotatable member with said slot extension may be further rotated to engage one of said lugs to thereby retain said lock bolt in unlocked position against the pressure of said single spring. 100

3. A lock as embodied in claim 1, and including manually operable means for causing a simultaneous inward movement of said lock and keeper bolts when the said rotatable members are set to permit the inward movement of said lock bolt. 110

4. In a lock of the kind described, and in combination, a slidably mounted lock bolt, a slidable keeper bolt, a plurality of independently mounted rotatable members each having a single radial slot therein, each of said rotatable members having the periphery thereof corrugated and the width of the spaces between said corrugation being equal 115 to the width of said slot, resilient means engaging said corrugated peripheries of said members, a single spring exerting pressure on said lock bolt and said keeper bolt tending to retain same in locked position, a plurality of lugs connected with said lock bolt, a plurality of separate and independently mounted controls for said rotatable members, an arcuate slot extension in one of said slots of one of said rotatable members whereby the rotatable member with said slot ex- 120 125 130

5 tension may be further rotated to engage one of said lugs to thereby retain said lock bolt in unlocked position against the pressure of said single spring, and a dial for each of said controls adapted for setting at varying indications, said rotatable members being adjustable to varying relative positions to said controls whereby said slots in said rotatable members may be prearranged 10 to align with said lugs at varying indications of said dials to permit the inward movement of said lock and keeper bolts.

5. A lock as embodied in claim 4, and including manually operable means for 15 causing a simultaneous inward movement of said lock and keeper bolts when the said rotatable members are set to permit the inward movement of said lock bolt, said manually operable means also being adapted to 20 move said keeper bolt inwardly and independently of said lock bolt upon the retainment of said lock bolt in unlocked position.

6. In a lock of the kind described, and in combination, a casing for said lock, a 25 removable cover for said casing, a slidably mounted lock bolt in said casing, a slidably mounted keeper bolt in said casing, said bolts adapted to project exteriorly of said casing when in locked position, a plurality of independently rotatable members in said 30 casing each having a single radial slot therein and the periphery of each of said rotatable members having corrugations and the width of the spaces between said corrugations being equal to the width of said slots,

a shaft for each of said rotatable members extending through said casing and said cover therefor, resilient means engaging said corrugations of said rotatable members, spring means exerting pressure on said lock 40 and keeper bolt normally retaining same in locked position, a plurality of lugs formed integrally with said lock bolt, a sleeve for each of said shafts supported in said casing and cover therefor, said sleeves being fixed 45 for relative movement with said shafts, said rotatable members being loosely mounted on said sleeves and each of said rotatable members having a plurality of openings therein, an arm integral with each of said sleeves 50 and each arm having a pin therein, each of said rotatable members being rotatably adjustable relatively to said sleeve and integral arm whereby said pin may engage within either of said openings in said members, a 55 manually operable control for each of said shafts, and a dial for each control adapted for relative movement with said sleeve co-operating therewith, each rotatable member being adjustable to varying prearranged 60 relative positions to said arm of its co-operating sleeve whereby said slots in said rotatable members may be prearranged to align with said lugs at varying positions of said dials to permit the inward movement of 65 said lock and keeper bolts into unlocked position.

In witness whereof I affix my signature.

JAMES VRBA.
